UNITED STATES PATENT OFFICE.

JACOB FRANK, OF CINCINNATI, OHIO, ASSIGNOR TO THE FRANK TEA & SPICE COMPANY, OF CINCINNATI, OHIO, A PARTNERSHIP.

DESIGN FOR A SPICE-BOX.

41,558.

Specification for Design.

Patented July 11, 1911.

Application filed April 11, 1910. Serial No. 554,885. Term of patent 14 years.

To all whom it may concern:

Be it known that I, JACOB FRANK, a citizen of the United States, residing at Cincinnati, in the county of Hamilton and State of Ohio, have invented a new and original Design for a Spice-Box, of which the following is a specification, reference being had to the accompanying drawing, forming part thereof.

Figure 1 is a top plan view. Fig. 2 is a side elevation. Fig. 3 is a bottom plan view.

The characteristic feature of the design is the diamond shaped body 1, with the circular top 2 of lesser cross section than the body, the top being also provided with the perforations 3 for sprinkling the spice. The top is of the screw cap type. The top por-

tion of the body assumes a horizontal plane flaring downwardly toward each corner, and the circular top is provided with an annular bead below the screw cap. The base of the body flares slightly upward at the corners, and the corners are all rounded. This diamond shape with the circumferential top presents a unique and very ornamental design of box.

I claim:—

The ornamental design for a spice box as shown and described.
